UNITED STATES PATENT OFFICE.

CARL J. SCHWARZE, OF ADRIAN, MICHIGAN, ASSIGNOR TO SCHWARZE ELECTRIC COMPANY, OF ADRIAN, MICHIGAN, A CORPORATION OF MICHIGAN.

BUZZER.

1,263,711.

Specification of Letters Patent. Patented Apr. 23, 1918.

Application filed August 23, 1917. Serial No. 187,742.

To all whom it may concern:

Be it known that I, CARL J. SCHWARZE, a citizen of the United States of America, residing at Adrian, in the county of Lenawee 5 and State of Michigan, have invented certain new and useful Improvements in Buzzers, of which the following is a specification, reference being had therein to the accompanying drawings.

10 The invention relates to electrically-operated buzzers and comprises the construction as hereinafter set forth.

In the drawings:

15 Figure 1 is a plan view of the buzzer with the cover of the casing removed;

Fig. 2 is a longitudinal section through the completed buzzer.

A is a base formed of pressed sheet-metal having a marginal flange B extending there- 20 above and rearward therefrom, terminating in one or more laterally-extending perforated ears C forming the securing means therefor. The base A is substantially rectangular in form and is provided with a de-

25 pressed panel D cut away at D'. E is a Z-shaped member having its central portion secured to said depressed panel, with the rearwardly-extending flange E' extending through the aperture therein and the out- 30 wardly-extending flange E² at one side of said panel. F are magnetic cores mounted upon the flange E² and extending parallel to each other and the base. G are magnet coils upon the cores. H is a non-magnetic bridge 35 between the outer ends of said cores. I is a striker-bar slidably secured in alined apertures in said flange E² and bridge H and extending between the coils G. J is an armature mounted on one end of the bar I,

40 being provided with an outwardly-extending and return-bent portion J'. K is a resilient vibrator mounted on the rearwardly-extending flange E' and extending outward through the aperture D' into the 45 open return bend J'. L is an insulated electrode also mounted on the flange E' but insulated therefrom, and K' L' are coöperating contacts on the members K and L. M is a cover which is formed of pressed sheet-

50 metal, being provided with tongues M' adapted to be sprung into engagement with apertures M² in the base. The cover M has a marginal flange, a portion of which extends into proximity to the outer end of the

striker I. O are terminal posts mounted 55 upon the base at one side thereof.

In operation the vibrator K, in coöperation with the electrode L and contacts K' L', will cause the reciprocation of the armature J, which in turn will reciprocate the striker 60 I, causing a succession of blows against the side of the casing M, which produces the sound.

What I claim as my invention is:

1. An electric buzzer, comprising a base 65 formed of pressed sheet-metal having a marginal rearwardly-extending flange thereabout terminating in one or more laterally-extending perforated ears forming the securing means, said base having a depressed panel, a magnet mounted on said depressed panel, an armature for said magnet movable parallel to said base, a striker-bar secured to said armature, and a cover for said depressed panel and magnet having a marginal flange in proximity to said striker-bar, against which the latter is adapted to im- 70 ping.

2. An electric buzzer, comprising a base 80 formed of pressed sheet-metal having a rearwardly-extending flange thereabout and a depressed panel, a magnet mounted on said depressed panel comprising a Z-shaped member having its central portion secured to said depressed panel, a rearwardly-ex- 85 tending flange projecting through an aperture in said panel and an outwardly-extending flange, magnet cores secured to said outwardly-extending flange and arranged par- 90 allel to each other on said base, a non-magnetic bridge member between the outer ends of said cores, a striker-bar slidably secured in alined apertures in said outwardly-ex- 95 tending flange and non-magnetic bridge, an armature mounted on said striker-bar, a 95

vibrator mounted on said rearwardly-ex- 100 tending flange and extending through the aperture in said depressed panel into operative relation to said armature, and a cover for said depressed panel and magnet formed 100 of pressed sheet-metal, being provided with diametrically opposite tongues for engaging corresponding apertures in said base, and one side of said cover being in proximity to the end of said striker-bar so as to be struck 105 thereby.

In testimony whereof I affix my signature.
CARL J. SCHWARZE.
